UNITED STATES PATENT OFFICE

173,050

TRUCK BUMPER

Ray A. Braunberger, Chicago, Ill.

Application February 19, 1954, Serial No. 29,125

Term of patent 14 years

(Cl. D14—6)

To all whom it may concern:

Be it known that I, Ray A. Braunberger, a citizen of the United States, residing at Chicago, State of Illinois, have invented a new, original, and ornamental Design for a Truck Bumper, of which the following is a specification, reference being had to the accompanying drawing, forming a part hereof, in which the figure is a perspective view of a truck bumper, showing my new design.

I claim:

The ornamental design for a truck bumper, as shown.
